GARMENT HANGER

James D. Coney, Chicago, Ill., assignor to Star-Service Hanger Division, L. A. Young Spring and Wire Corporation, Detroit, Mich., a corporation of Michigan

Application August 13, 1942, Serial No. 454,683

8 Claims. (Cl. 223—88)

This invention relates to improvements in garment hangers.

The main objects of this invention are:

First, to provide a garment hanger which may be formed entirely of fibrous material, mainly of multi-ply paper tubing which is very strong and rigid and attractive in appearance.

Second, to provide a garment hanger having these advantages which may be very economically produced.

Objects relating to details and economies of the invention will appear from the description to follow. The invention is defined and pointed out in the claims.

Preferred embodiments of the invention are illustrated in the accompanying drawing, in which:

Fig. 1 is a side elevation of a garment hanger of desirable form embodying the features of my invention partially sectioned to show structural details.

Fig. 2 is a side elevation of one of the coupling members for the tubular arms of the strut.

Fig. 3 is an enlarged fragmentary view in section on the broken line 3—3 of Fig. 1.

Fig. 4 is a fragmentary side elevation of a modified form of suspending member, the suspending member having an eye instead of a hook.

Fig. 5 is a modified embodiment in which the downwardly diverging arms are formed integrally, the same coupling members being used for the arms and strut as shown in the embodiment of Fig. 1.

The embodiment of my invention illustrated in Figs. 1 to 3 inclusive comprises a pair of downwardly diverging tubular arms 1 formed of fibrous material, preferably multi-ply paper stock as is shown in Fig. 3.

The suspending hook 2 is formed of fibrous material preferably multi-ply stock as shown in Fig. 3. This suspending hook or member 2 is provided with downwardly diverging dowels 3 which are telescoped into the upper ends of the arms, the upper ends of the arms being collapsed or flattened at 4 as shown in Fig. 3 to closely embrace the sides of the dowels, these telescoping parts being secured together by adhesive indicated at 5.

The suspending member is shouldered at 6 at the base of the dowels, the ends of the arms abutting this shoulder. These shoulders facilitate assembling and also add to the appearance.

The tubular strut 7 is also of fibrous material, preferably of multi-ply paper, and is secured to the lower ends of the yoke arms 1 by means of the coupling members 8. These coupling mem-

bers are formed of fibrous material preferably multi-ply stock of the same kind as the suspending member. These coupling members have diverging dowels 9 which are telescoped into the lower ends of the arms 1 and the ends of the strut, the arms of the strut being preferably collapsed or flattened as shown so that the sides of the dowels are closely embraced the same as the dowels of the suspending member.

10 It will be noted that these coupling members have shoulders 10 and 11 with which the ends of the arms and of the strut abut, and preferably have curved or rounded outer edges 12 which merge into the upper and lower sides respectively of the yoke arms and the strut, providing effective rounded shoulders for the hanger and also adding to the appearance.

In the embodiment shown in Fig. 4, the suspending member 19 has an eye instead of a hook.

In the embodiment shown in Fig. 5, the yoke arms 20 are formed integrally, the suspending hook 21 of wire being arranged through the flattened or collapsed apex portion 22 of the tube forming the arms 20. Coupling members 8 are employed to connect these arms to the strut 7 in the same manner as in the embodiment of Fig. 1.

My improved garment hanger is preferably formed entirely of fibrous material although certain features of my invention may be embodied in a structure such as shown in Fig. 5.

I have illustrated and described my improvements in highly satisfactory embodiments. I have not attempted to illustrate or describe certain other embodiments which I contemplate as it is believed that this disclosure will enable those skilled in the art to which my invention relates to embody or adapt the same as may be desired.

Having thus described my invention, what I claim as new and desire to secure by Letters Patent, is:

1. In a garment hanger, the combination of a yoke comprising downwardly diverging tubular arms of fibrous material, a suspending hook of flat sheet multi-ply fibrous material having downwardly diverging dowels telescoped into the upper ends of said yoke arms, said dowels having substantially parallel upper and lower edges, said yoke arms being collapsed to receive said dowels and closely embracing the sides and the edges thereof, such telescoping parts being adhesively secured together, said hook being provided with shoulders at the bases of the dowels with which the ends of the arms abut, a tubular strut of fibrous material, and coupling members of flat

sheet multi-ply fibrous material having diverging dowels provided with substantially parallel upper and lower edges and telescoped within the lower ends of the yoke arms and the ends of the tubular strut, such ends being collapsed to receive said dowels and to closely embrace the sides and the edges of the coupling member dowels and the telescoping parts being adhesively secured together, the coupling members having shoulders at the base of the dowels with which the ends of said arms and strut abut, the coupling members having curved outer edges merging into the upper and lower sides respectively of the yoke arms and strut.

2. In a garment hanger, the combination of a yoke comprising downwardly diverging tubular arms of fibrous material, a suspending hook of flat sheet multi-ply fibrous material having downwardly diverging dowels telescoped into the upper ends of said yoke arms, said dowels having substantially parallel upper and lower edges, said yoke arms being collapsed to receive said dowels and closely embracing the sides and the edges thereof, such telescoping parts being adhesively secured together, a tubular strut of fibrous material, and coupling members of flat sheet multi-ply fibrous material having diverging dowels provided with substantially parallel upper and lower edges and telescoped within the lower ends of the yoke arms and the ends of the tubular strut, such ends being collapsed to receive said dowels and to closely embrace the sides and the edges of the coupling member dowels and the telescoping parts being adhesively secured together.

3. In a garment hanger, the combination of a yoke comprising downwardly diverging tubular arms of fibrous material, a tubular strut of fibrous material, and coupling members of flat sheet multi-ply fibrous material having diverging dowels provided with substantially parallel upper and lower edges and telescoped within the lower ends of the yoke arms and the ends of the tubular strut, such ends being flattened to closely embrace the sides and the edges of the coupling member dowels and the telescoped parts being adhesively secured together, the coupling members having shoulders at the base of the dowels with which the ends of said arms and strut abut, the coupling members having curved outer edges merging into the upper and lower sides respectively of the yoke arms and strut.

4. In a garment hanger, the combination of a yoke comprising downwardly diverging tubular arms of fibrous material, a tubular strut of fibrous material, and coupling members of flat sheet multi-ply fibrous material having diverging dowels provided with substantially parallel upper and lower edges and telescoped within the lower ends of the yoke arms and the ends of the tubu-

lar strut, such ends being flattened to closely embrace the sides and the edges of the coupling member dowels and the telescoped parts being adhesively secured together.

5. In a garment hanger, the combination of a yoke comprising downwardly diverging tubular arms of fibrous material, a suspending member of fibrous flat sheet material having dowels provided with substantially parallel upper and lower edges and telescoped and secured within the upper ends of said yoke arms, said suspending member being provided with shoulders at the bases of the dowels with which the ends of the arms abut a tubular strut of fibrous material, and coupling members of fibrous flat sheet material having dowels provided with substantially parallel upper and lower edges and telescoped and secured within the lower ends of the yoke arms, the coupling members having shoulders at the base of the dowels with which the ends of said arms and strut abut, the coupling members having curved outer edges merging into the upper and lower sides respectively of the yoke arms and strut.

6. In a garment hanger, the combination of a yoke comprising downwardly diverging tubular arms of fibrous material, a suspending member of fibrous flat sheet material having dowels provided with substantially parallel upper and lower edges and telescoped and secured within the upper end of said yoke arms, a tubular strut of fibrous material, and coupling members of fibrous flat sheet material having dowels provided with substantially parallel upper and lower edges and telescoped and secured within the lower ends of the yoke arms and the ends of the tubular strut.

7. In a garment hanger, the combination of a yoke comprising downwardly diverging tubular arms of fibrous material, a tubular strut of fibrous material, and coupling members of fibrous flat sheet material having dowels provided with substantially parallel upper and lower edges and telescoped and secured within the lower ends of the yoke arms and the ends of the tubular strut, the coupling members having shoulders at the base of the dowels with which the ends of said arms and strut abut, the coupling members having curved outer edges merging into the upper and lower sides respectively of the yoke arms and strut.

8. In a garment hanger, the combination of a yoke comprising downwardly diverging tubular arms of fibrous material, a tubular strut of fibrous material, and coupling member of fibrous flat sheet material having dowels provided with substantially parallel upper and lower edges and telescoped and secured within the lower ends of the yoke arms and the ends of the tubular strut.

JAMES D. CONEY.
